TIE FOR CONCRETE WALL FORMS

William D. Harder, Chicago, Ill.

Application June 25, 1947, Serial No. 756,961

3 Claims. (Cl. 287—109)

1
 The present invention relates to a tie for concrete wall forms. In the art of building concrete walls, first a pair of spaced wall forms are erected, the latter consisting of a plurality of panels laid in an edge to edge relation. For the purpose of holding a pair of erected wall forms in a proper spaced, rigid relation ties are employed, which by their ends are rigidly affixed to the opposing panels and in a transverse relation with the space defined by the two wall forms into which cement mixture is poured. When the cement mixture has solidified the panels are disconnected from the ends of the ties and the former are then removed from the finished concrete wall. Usually such ties are left in the concrete wall.

The principal object of the present invention is the provision of a tie for the purpose above indicated consisting of a tubular body portion with the solid end portions extending therefrom, the latter, on completion of a concrete wall being removable from said tubular body portion, thereby saving material.

Another object of the present invention is the provision of a tie of the type above indicated, wherein the end portions thereof may be rigidly connected to the tubular portion thereof, and which on completion of a concrete wall and on removal of the panels aforesaid may be disconnected from said tubular portion of the tie and removed therefrom by an exceedingly simple operation.

A still further object of the present invention is the provision of comparatively simple connecting means between the tubular body portion of the tie of the type hereinabove indicated and the solid end portion thereof, whereby on application of force to said solid end portions of the tie the said connecting means may be rendered inoperative for the purpose of removing said end portions from said tubular body portion of the tie.

A still further object of the present invention is the provision of a method for connecting of an oblong solid piece of material with a tubular holder within which the former is insertable.

With the above general objects in view and others that will appear as the invention is better understood, the same consists in the novel construction, combination and arrangement of parts hereinafter more fully described, illustrated in the accompanying drawing and pointed out in the appended claims.

In the drawing forming a part of this application and in which like designating characters refer to corresponding parts throughout the several views:

2
 Fig. 1 is a face elevational view, partly broken away, of the tie constituting the present invention, showing the tubular body portion thereof in an operative position with relation to the end portions thereof;

Fig. 2 is a similar view with the end portions of the tie driven inwardly into the tubular portion thereof, after the rigid connection therebetween has been severed, preparatory to the removal of the end portions from the tubular portion of the tie;

Fig. 3 is a face elevational view of one end of the tie;

Fig. 4 is a face elevational view of one end portion of the tie; and

Fig. 5 is an enlarged cross-sectional view on line 5—5 of Fig. 3.

Referring in detail to the present drawing there is shown a tie including the tubular portion or sleeve 10 thereof. Said sleeve 10 is of a flat formation, including a pair of opposed wider walls, and a pair of narrower edge walls, as is clearly seen in Fig. 5. Cooperating with each end of sleeve 10 and insertable therewithin, is a solid portion of the tie or tongue 11. When tongues 11 are in an operative position with relation to sleeve 10, as shown in Fig. 1, the tie is ready for use in the construction of concrete walls. In such use sleeve 10 will remain in the space defined by a pair of opposed form walls between which cement mixture is poured, with said sleeve 10 ultimately remaining embedded in the concrete wall when built. Tongues 11 extend between the panels outwardly of the space defined by a pair of panel form walls, and are rigidly affixed to the panels for maintaining the two form walls in a rigid spaced relation. When the concrete wall has been made, the panels are thereupon disconnected from tongues 11, and the latter are thereupon disconnected from sleeve 10 and removed therefrom.

The outer end of each tongue 11 may be arcuate and provided with aperture 12 by means of which the tongue may be rigidly affixed to the panels. The inner end of each tongue 11, and on each edge thereof, is provided with a plurality of opposed teeth 13. These teeth are struck out in tongue 11. Each tooth 13 has a straight face 14, which is in a perpendicular relation with the longitudinal axis of tongue 11, and an inclined face 15, the outer end of which in conjunction with said straight face 14 defines sharp point 16 of the tooth.

The inner end of each inclined face 15 is in the nearest proximity of the longitudinal center of

tongue 11, and away from the free end of tongue 11 at which aperture 12 is located. Each pair of adjacent teeth 13 at each edge of tongue 11 is spaced by straight wall 17. The several walls 17 are disposed on a continuing plane in parallelism with the edges of tongue 11 but removed therefrom towards the center of the tongue. It will be therefore seen that the wider transverse edge of each tooth 13 is nearest to the free end of tongue 11, while the narrower portion of each tooth 13 is farthest from the free end of said tongue. Except for spacing walls 17 between teeth 13, the latter in all respects are identical with teeth in a ripsaw.

When the toothed end of each tongue 11 is inserted within the end of sleeve 10, thereupon by a suitable machine or tool crimping is imparted to the opposed edges of sleeve 10 and adjacent said teeth 13 for effecting interlocking between sleeve 10 and teeth 13. This crimping includes tearing of sleeve 10 transversely thereof and along the plane of faces 14 in a pair of opposed teeth 13, as at 18. This action results in an indent 19, which is pressed towards the longitudinal center of sleeve 10 and tongue 11, until the same is brought in contact with inclined face 15 of each tooth 13, and until the free end of each indent 19 reposes within the corner defined by face 14 and wall 17 in each tooth 13. By virtue of this action indents 19 are interlocked with teeth 13 in a rigid manner, with indents 19 forming transverse obstructions for teeth 13, so that no reasonable degree of pull upon tongues 11 in the direction of their free ends will be able to disconnect or withdraw tongue 11 from sleeve 10.

The interlocking between tongues 11 and sleeve 10, resulting from teeth 13 and indents 19, respectively, will be sufficient to withstand all stresses upon the tie for maintaining a pair of spaced form walls when under pressure of cement mixture poured therebetween while building a concrete wall.

When a concrete wall has solidified and the panels are disconnected from tongues 11 and removed from a concrete wall built, the removal of tongues 11 from sleeve 10, is a comparatively simple matter. To accomplish this object, all that is required is application of force at the free ends of tongues 11, as by hammer or a like instrument, for driving tongues 11 and sliding them inwardly of sleeve 10. This action causes inclined faces 15 to ride upon the contacting faces of indents 19 for forcing the latter towards the edge lines of sleeve 10 and away from teeth 13 to substantially assume the continuing perimeter of sleeve 10, as is seen in Fig. 2. When this was accomplished, with indents 19 out of the path of teeth 13 or of their straight faces 14, the entire tongue 11 may then be removed bodily from sleeve 10 by pulling tongue 11 in the opposite direction, that is towards its free end. The tongue thus removed may be reused many times, or if preferred the same may be completely driven into sleeve 10 as is shown at the upper end of the tie in Fig. 2. The removal of tongues 11 from sleeve 10 is predicated upon sleeve 10 remaining permanently embedded within a concrete wall when the latter has been made. Otherwise, when sleeve 10 is wrapped in a paper lining, the same may be bodily removed from the solidified concrete wall, by exerting pulling force upon one of tongues 11, but in that latter event no preliminary driving of tongue 11 into sleeve 10 should be resorted to, because such driving of tongue 11 into sleeve 10 would cause deflection of indents

19 from teeth 13 and consequent severance of connection between tongues 11 and sleeve 10.

The solidified concrete around indents 19 will be no obstacle for deflecting the same outwardly and away from teeth 13 when tongue 11 is driven inwardly of sleeve 10, because force of sufficient degree applied at tongue 11 to so drive the same will cause compaction of the surrounding concrete for permitting the deflection of said indents 19.

While there is described herein a preferred embodiment of the present invention, it is nevertheless to be understood that minor changes may be made therein without departing from the spirit and scope of the invention as claimed.

What I claim as new is:

1. A tie of the class described comprising a hollow member, an extensible member receivable within the end of said hollow member in a longitudinal coaxial relation therewith, said extensible member being provided with a transverse notch, and a crimp made in said hollow member, said crimp entering said notch for rigidly retaining said extensible member within said hollow member, on application of force for shifting said extensible member within said hollow member said crimp being adapted for deflection from said notch for severing the engagement between said hollow member and said extensible member preparatory to the withdrawal of the latter from the former.

2. A tie of the class described comprising a hollow member, said hollow member being substantially of a rectangular formation on transverse cross-section, an oblong flat tongue fitted within the end of said hollow member, a plurality of teeth struck out at the opposed edges of said tongue adjacent the inner end thereof, said teeth defining a plurality of notches, and a plurality of indents made in the opposed edges of said hollow member, said indents entering said notches for rigidly retaining said extensible member within said hollow member, on application of force to said extensible member for shifting the same within said hollow member, said indents being deflected by said teeth from within said notches for severing the engagement between said hollow member and said extensible member preparatory to the withdrawal of the latter from the former.

3. A tie of the class described comprising a hollow member, said hollow member being substantially of a rectangular formation on transverse cross-section, an oblong flat tongue receivable within the end of said hollow member a plurality of teeth struck out in the opposed edges of said tongue, each of said teeth having a face on a plane substantially transverse with relation to said tongue and a face on an incline with relation to the longitudinal axis of said tongue, the first named face of each tooth being in the nearest proximity to the outer free end of said tongue, the second named face of each tooth being farther removed from the outer free end of said tongue, said faces in the pairs of adjacent teeth defining notches, and a plurality of indents made in the opposed edges of said hollow member, said indents entering said notches, said notches bearing against the said first named faces of said teeth for preventing the shifting movement of said tongue in the direction away from the center of said hollow member, on shifting of said tongue toward the center of said hollow member said second named faces of said teeth riding upon said indents for deflecting the latter from within said

notches preparatory to the withdrawal of said tongue from said hollow member.
